UNITED STATES PATENT OFFICE.

ALBA R. D. REESE, OF BISBEE, ARIZONA.

FLUID ENGINE.

Application filed December 24, 1925, Serial No. 77,548. Renewed January 27, 1927.

My invention aims to provide a rather simple, yet an exceptionally powerful engine, having a master cylinder containing a master piston which is operated by fluid supplied under pressure from a plurality of force pumps, the construction being such that only a small amount of power, compared to that derived from the engine is necessary to actuate said pumps.

Another object of the invention is to provide an engine of the type set forth in which the master cylinder, the fluid reservoir, the pumps, etc., are all compactly related.

With the foregoing in view, the invention resides in the novel subject matter herein-after described and claimed, the description being supplemented by the accompanying drawings.

Figure 1 is a vertical sectional view on the plane indicated by line 1—1 of Fig. 2 showing the master piston at the end of its working stroke.

Figure 2 is a vertical section at right angles to Fig. 1 as indicated by line 2—2 of the latter.

Figure 3 is a view similar to Fig. 1 but showing the master piston at the end of its exhaust stroke which is the beginning of its power stroke.

Figure 4 is a top plan view.

Figure 5 is a horizontal sectional view on the plane indicated by line 5—5 of Fig. 2.

Figure 6 is an enlarged detail sectional view partly in elevation showing a different form of exhaust valve structure which may be used if desired, this structure being shown in open position.

Figure 7 is a view similar to Fig. 6 but showing the valve structure closed.

Figure 8 is a horizontal sectional view taken on line 8—8 of Fig. 6.

The form of construction herein disclosed may be considered as preferred, and while this construction will be hereinafter specifically described, it is to be understood that within the scope of the invention as claimed, variations may be made.

The numeral 9 designates a master cylinder which is disposed vertically and provided at its upper end with a head 10, the lower end of said cylinder being also closed by a plate 11. A master piston 12 is mounted in the cylinder 9 and a crank shaft 13 is provided below said cylinder, appropriate

connecting means such as the piston rod 14 and pitman 15, being provided between the master piston 12 and said crank shaft. The rod 14 passes through an opening 16 in the plate 11 and suitable packing means (not shown) may be provided at this point to prevent leakage of fluid around the rod. At 17, a cross head is shown connected with the rod 14 and the pitman 15 and slidably engaged with appropriate guides 18. The crank shaft 13 is shown mounted in bearings 19 upon a base 20, from which supports 21 rise to carry the cylinder 9 and associated parts. I wish it understood however that all parts below the cylinder having any movement in the operation of the engine, may well be encased in a crank case if desired, instead of employing the base 20 and supports 21.

A jacket 22 surrounds the master cylinder 9, and the space between said jacket and cylinder forms with the hollow interior of the head 10, a fluid reservoir. A plurality of spaced openings 23, for a purpose to appear, are formed through the wall of the cylinder 9 to establish communication first between the lower end of the cylinder and the reservoir and then between the upper portion of said cylinder and the reservoir, said openings being controlled by the piston 12. These openings are located near the lower end of the cylinder and they establish communication between the fluid reservoir and the cylinder space under the piston 12 until the latter nears the lower end of its working stroke. The piston then passes across the openings and later assumes a position below them as shown in Figs. 1 and 2.

Radial passages 24 are in valved communication with the lower end of the master cylinder 9, by means of outwardly opening check valves 25, the outer ends of these passages being in communication with a plurality of relatively small, auxiliary cylinders 26 which may well be cast integrally with the master cylinder and its jacket, and closed at their lower ends by the plate 11. Other passages 27 are formed within the fluid reservoir, the upper ends of these passages communicating at 28 with the upper end of the master cylinder 9, while their lower ends are in valved communication with the passages 24, by upwardly opening check valves 29.

Auxiliary or pump pistons 30 are slidable

in the auxiliary cylinders 26 and may well be raised by springs 31. Upon each ascent of these pistons, they draw fluid from the fluid reservoir and the interior of the master cylinder 9, through the passages 24 and into the auxiliary cylinders 26, as will be clear from an inspection of Fig. 3. When the pistons 30 are forced downwardly however, they drive the fluid through the passages 27 and into the master cylinder 9 above its piston 12 so as to effect a downward or working stroke of the latter. For so depressing the pistons 30, I prefer to make use of a pair of shafts 32 having cams 33 for engaging the upper ends of said pistons. I have shown these shafts connected with each other by sprockets and a chain 34, and a driving motor 35 has been illustrated, geared as at 36, to one of these shafts. The two shafts 32 are rapidly operated and the pumps actuated thereby supply the fluid to the master cylinder 9 to force the master piston 12 thereof downwardly upon its working strokes. In a single cylinder engine, momentum, stored for instance in a fly-wheel, is relied upon to raise the piston, but I also contemplate multiple cylinder engines in which the power from the several cylinders overlaps and thus each piston is raised by the power stroke of another piston. During the upward piston travel, exhaust of fluid takes place from the upper end of the cylinder into the fluid reservoir, through exhaust means to be hereinafter described, and as soon as the piston 12 uncovers the openings 23, fluid from the reservoir may enter the cylinder 9 under said pistons as will be clear from Fig. 3.

A plurality of exhaust ports 37 are shown from the upper end of the master cylinder 9, into the portion of the fluid reservoir within the head 10, and an inwardly opening valve 38 is provided for said exhaust ports. In the present showing, this valve is carried by a spring-raised stem 39 which co-operates with an appropriate rocker 40, the latter being operatively associated with a push rod 41 which is actuated by a cam shaft 42 suitably geared to the crank shaft 13. The valve 38 is of course closed when fluid forced through the passages 27 into the upper end of the cylinder 9, is driving the master piston 12 downwardly. When this working stroke is completed however, the exhaust valve 38 opens as shown in Figs. 1 and 2. During descent of the piston 12, as soon as the latter passes the openings 23, some of the fluid from the upper portion of the cylinder 9 may run through these openings into the fluid reservoir. As the piston then ascends, the remainder of the fluid from the cylinder 9 is exhausted through the ports 37, into said reservoir, and by the time the exhaust stroke is complete, the valve 38 again closes and another power stroke will

take place. The fluid pumps 30-26, of course continually operate while the piston is ascending, but as the terminals 28 of the discharge passages 27 from these pumps are then in open communication with the exhaust ports 37, the fluid discharged by the pumps in the cylinder is immediately expelled into the fluid reservoir.

In Figs. 6, 7 and 8, a different form of exhaust valve structure has been shown. In these views, auxiliary exhaust ports 43 are formed in the wall of the cylinder 9, adjacent the upper end of this cylinder. These ports are controlled by valve plates 44 which slidably engage the cylinder wall. In the construction shown, each of these valve plates is provided with two parallel inward projections 45 slidably received in sockets 46, said sockets projecting outwardly from a head 47 carried by a neck 48, said neck being secured to the valve 38. The valve plates 44 are pressed against the wall of the cylinder 9 by short coiled springs 49 arranged between the plates and the heads 47. It will thus be seen that opening and closing movements of this valve 38, will similarly move the valve plates 44 to open and closed positions.

By employing the valve construction just described, quick exhaust of fluid from the cylinder may take place so that the piston 12 encounters little resistance on its upward strokes.

The improved engine is rather simple and inexpensive, yet will be highly efficient. The fluid used in its operation is preferably, although not necessarily oil, and the engine merely utilizes well known laws of pressure or hydraulics, in its operation. If the piston 12 be of an area, say ten times as great as the combined areas of the pistons 30, the force will be multiplied in the same proportion, it being of course understood that the movement of the piston 12 is slow with respect to the travel of the auxiliary pistons 30.

As good results are obtainable from the general structure disclosed, it may if desired be followed. However, as above set forth, variations may be made within the scope of the invention as claimed. For instance, instead of having the cams 33 act directly on the plungers 30, rockers similar to the rockers 40 may be interposed between said cams and plungers, if desired.

I claim:

1. A fluid engine comprising a master cylinder and a master piston therein, a crank shaft and connecting means between the same and the master piston, a fluid reservoir surrounding the master cylinder, a plurality of force pumps in valved communication with said fluid reservoir and said master cylinder, means independent of said crank shaft for operating said pumps to

inject fluid into the master cylinder to operate the master piston, and fluid exhaust means from said cylinder to said fluid reservoir, including valve means synchronized with the crank shaft.

2. A fluid engine comprising a master cylinder and a master piston therein, a crank shaft and connecting means between the same and the master piston, a fluid reservoir surrounding the master cylinder, a plurality of auxiliary cylinders in valved communication with said reservoir and said master cylinder, auxiliary pistons in said auxiliary cylinders for drawing fluid from said reservoir and forcing it into said master cylinder to operate the master piston, means independent of said crank shaft for operating said auxiliary pistons, and valved fluid exhaust means from said master cylinder to said fluid reservoir, including valve means synchronized with the crank shaft.

3. A fluid engine comprising a master cylinder and a master piston therein, a crank shaft and connecting means between the same and said master piston, a fluid reservoir surrounding the master cylinder, the latter having openings into said reservoir controlled by said master piston, passages in valved communication with the lower end of said master cylinder, a plurality of auxiliary cylinders in communication with said passages, fluid supply passages for the master cylinder leading to the upper end of the latter and in valved communication with said auxiliary cylinders, auxiliary pistons in said auxiliary cylinders for drawing

fluid from the lower end of the master cylinder and the fluid reservoir and forcing it into the master cylinder to operate the master piston, and exhaust means from the upper end of the master cylinder into the fluid reservoir including valve means synchronized with the crank shaft.

4. In a fluid engine, a cylinder having main exhaust portage in its head and an inwardly opening valve therefor, said cylinder also having additional exhaust ports through its wall adjacent said head, and spring-pressed valve means for said additional ports, said spring-pressed valve means being carried by said first named valve and slidably engaging said cylinder wall.

5. A fluid engine comprising a master cylinder and a master piston therein, a crank shaft and connecting means between the same and the master piston, a jacket surrounding said master cylinder and spaced therefrom, a hollow head on one end of said cylinder and connecting therewith and with the space between said jacket and cylinder, said space and hollow head forming a fluid reservoir, a valve to open and close the communication between said hollow head and cylinder, means synchronized with said crank shaft for operating said valve, a plurality of force pumps in valved communication with said master cylinder, and means for operating said pumps to inject fluid into the master cylinder to operate said master piston.

In testimony whereof I have hereunto affixed my signature.

ALBA R. D. REESE.
